ISAAC HARTER, OF DONGAN HILLS, NEW YORK, ASSIGNOR TO THE BABCOCK & WILCOX COMPANY, OF BAYONNE, NEW JERSEY, A CORPORATION OF NEW JERSEY.

ACCESSORY FOR STEAM BOILERS.

1,412,865.

Specification of Letters Patent. Patented Apr. 18, 1922.

Application filed October 12, 1920. Serial No. 416,456.

To all whom it may concern:

Be it known that I, ISAAC HARTER, a citizen of the United States, residing at Dongan Hills, in the county of Richmond and 5 State of New York, have invented certain new and useful Improvements in an Accessory for Steam Boilers, of which the following is a specification.

In modern boiler installations where the 10 boilers are thoroughly protected from radiation losses by a covering of heat insulation, the condensed water in the discharge pipe from the safety valve is likely to freeze in cold weather, and such freezing, even 15 though the safety valve itself opens properly under excessive boiler pressure, is likely to result in a boiler explosion. In accordance with my invention, provision is made for normally discharging the steam 20 blown from the safety valve to the space without the boiler room, but constructed and arranged to permit the steam to be discharged adjacent to the safety valve in case 25 of a closure of the discharge pipe, such as is liable to result from freezing of the condensed steam therein.

My invention will best be understood by reference to the accompanying drawings, in which Figure 1 is a side elevation, partially in section, of a device embodying one 30 form of my invention; Figs. 2 and 3 are similar views showing modified forms of my invention, and Fig. 4 is a side elevation illustrating a still further modification.

35 Like reference characters indicate like parts throughout the drawings.

Referring now to the drawings, and first to Fig. 1, 10 is a steam boiler to which is fitted a safety valve 11 which may be of any 40 desired construction. To the safety valve 11 is connected a discharge nozzle 12, the nozzle being in sufficiently good thermal relation to the safety valve and the boiler to prevent freezing of any liquid therein.

45 A pipe 13 discharges the steam at a desired point, as through the roof or the side walls of the boiler setting. The inner end of the pipe 13 is preferably flared, as at 14, so as to form an enlarged end which surrounds the discharge end of the nozzle 12, and thus forms therewith a connection which is open to the atmosphere. The inner end of the pipe 13 is preferably kept in axial alignment with the discharge nozzle 50 12 by a member 15 which is clamped to

the nozzle 12, as at 16, and which is provided with arms extending outwardly beneath the flared edge 14 of the pipe 13, the arms being provided with notches, as at 17, within which the flared edge is received. 60 A drain pipe 18 is preferably connected to the nozzle 12.

In operation, the steam discharged from the safety valve creates an aspirating action within the pipe 13, and all of the steam 65 passes through the pipe 13 to the desired discharge point. In case of closure of the pipe 13, however, as by freezing of the condensed water therein, the steam discharged from the safety valve 11 will pass from 70 the discharge end of the nozzle 12 beneath the flared end 14 of the discharge pipe and to the atmosphere within the boiler room, so that the boiler is, in any case, relieved 75 of excessive pressure.

In the arrangement shown in Fig. 2, the discharge nozzle 12 and the lower flared end 14 of the discharge pipe are surrounded by a bowl 19 fitted around the discharge nozzle 12, as at 20, and open at its upper 80 end, as at 21. The bowl is preferably provided with a drain pipe 22 which may be connected to the drain pipe 18 for the discharge nozzle, as at 23. The provision of the bowl 19 serves to direct the steam which 85 may be discharged from the open connection between the discharge nozzle 12 and the discharge pipe 13 upwardly, and thus prevent injury to an operator who might be on top of the boiler when steam is blown from the 90 safety valve.

Fig. 3 illustrates a further modification of my invention, in which the top of the bowl 19 is provided with a cover 24 which forms a loose fit 25 around the discharge 95 pipe 13 and normally rests on the bowl 19. In case of discharge of steam through the bowl, the cover 24 is lifted, thus permitting escape of the steam.

In the construction shown in Fig. 4, a 100 plurality of plates 26 are hinged at 27 to the upper edge of the bowl 19^a and normally rest against the lower flared end 14^a of the discharge pipe 13. The flared end, in the form here shown, is preferably octagonal, 105 or is otherwise angularly formed, and the plates 26 are so formed as to completely close the space above the bowl when they rest against the flared end 14^a in the positions indicated by the full lines. In case 110

of closure of the discharge pipe 13, the pressure created by the steam in the bowl 19^a readily blows open the plates 26 and permits the escape of the steam upwardly to the atmosphere.

What I claim and desire to secure by Letters Patent of the United States is:

1. The combination with a steam boiler safety valve having a steam outlet, of a conduit through which the steam emerging from the outlet normally passes, the conduit entrance and the steam outlet being arranged to permit the steam to pass from the outlet to the atmosphere when the conduit is 15 clogged or accidentally closed.

2. In combination, a safety valve for a steam boiler, connections for normally discharging the steam emerging from the valve to a desired point, said connections being 20 constructed and arranged to permit the steam, when said connections become clogged, to escape to the atmosphere at a point short of the clogged part.

3. In combination, a safety valve for a 25 steam boiler, a pipe for discharging the steam blown from the valve to a desired point, and a connection between said valve and said pipe constructed and arranged to cause the steam normally to pass from said valve through said pipe and to pass from said valve directly to the atmosphere in case of the closure of said pipe.

4. In combination, a safety valve for a 35 steam boiler, a pipe for discharging the steam blown from the boiler to a desired point, and a connection between said valve and said pipe open to the atmosphere and constructed and arranged to cause the steam normally to pass from said valve through 40 said pipe.

5. In combination, a safety valve for a steam boiler, a pipe for discharging the steam blown from the boiler to a desired point, and a nozzle connected to said valve 45 and leading to said pipe and constructed and arranged to cause the steam blown from said valve normally to discharge through said pipe and to escape to the atmosphere in case of the closure of said pipe.

50 6. In a steam boiler provided with a safety valve, a discharge nozzle for said valve in sufficiently good thermal relation to said valve and to the boiler to prevent freezing of liquid therein under normal operating conditions, and a pipe for discharging the steam blown from said valve to a desired point, the connection between said nozzle and said pipe being constructed and arranged to cause the steam blown from said valve normally to pass through said pipe but to pass

directly to the atmosphere in case of closure of said pipe.

7. In a steam boiler provided with a safety valve, a discharge nozzle for said valve in sufficiently good thermal relation to said valve and to the boiler to prevent freezing of liquid therein under normal operating conditions, and a pipe for discharging the steam blown from said valve to a desired point, the connection between said nozzle and said pipe being constructed and arranged to cause the steam blown from said valve normally to pass through said pipe but to pass upwardly directly to the atmosphere in case of closure of said pipe.

75 8. In combination, a safety valve for a steam boiler, a discharge nozzle connected thereto, and a pipe for discharging the steam blown from said valve to a desired point and provided with a flared end larger than and surrounding said nozzle.

80 9. In combination, a safety valve for a steam boiler, a discharge nozzle connected thereto and in sufficiently good thermal relation to said valve and to said boiler to prevent freezing of liquid therein, and a pipe for discharging the steam blown from said valve to a desired point and provided with a flared end larger than and surrounding said nozzle.

85 10. In combination, a safety valve for a steam boiler, an upwardly directed discharge nozzle connected to said valve, a bowl fitted about said nozzle and open at its upper end, and a pipe for discharging the steam blown 95 from said valve to a desired point and having its inner end extending into said bowl and surrounding said nozzle.

90 11. In combination, a safety valve for a steam boiler, an upwardly directed discharge 100 nozzle connected to said valve, a bowl fitted about said nozzle and open at its upper end, and a pipe for discharging the steam blown from said valve to a desired point and having its inner end flared and arranged in axial alignment with and surrounding said nozzle, free communication being provided between said nozzle and the atmosphere through said bowl.

105 12. In combination, a safety valve for a steam boiler, an upwardly directed discharge nozzle connected to said valve, a bowl fitted about said nozzle and open at its upper end, a pipe for discharging the steam blown 110 from said valve to a desired point and having its inner end extending into said bowl and surrounding said nozzle, and a drain pipe connected to the lower part of said bowl.

ISAAC HARTER.
